Primary Examiner — Catherine S Posthauer*(74) Attorney, Agent, or Firm* — Koffsky Schwalb LLC;
 Mark I. Koffsky(57) **CLAIM**

I claim the ornamental design for a package insert, as shown and described.

DESCRIPTION

FIG. 1 is a top plan view of a package insert, shown in an unassembled configuration;

FIG. 2 is a bottom, front, right perspective view thereof, shown in an assembled configuration;

FIG. 3 is a bottom, rear, left perspective view thereof;

FIG. 4 is a top, front, right perspective view thereof;

FIG. 5 is a top, rear, left perspective view thereof;

FIG. 6 is a top view thereof;

FIG. 7 is a bottom view thereof;

FIG. 8 is a front view thereof;

FIG. 9 is a rear view thereof;

FIG. 10 is a left view thereof; and,

FIG. 11 is a right view thereof.

The dashed lines represent fold lines that form part of the claimed design.
